UNITED STATES PATENT OFFICE.

JAMES R. BETT, OF LORD, MARYLAND, ASSIGNOR TO ROBERT B. BETT, OF CHEHALIS,
WASHINGTON.

HAT-MIRROR.

Specification of Letters Patent. Patented July 21, 1914.

1,104,608.

Application filed February 19, 1913. Serial No. 749,457.

To all whom it may concern:

Be it known that I, JAMES R. BETT, a citizen of the United States, residing at Lord, in the county of Allegany and State of Maryland, have invented certain new and useful Improvements in Hat-Mirrors, of which the following is a specification.

My invention relates to new and useful improvements in hat mirrors, the object of which is to provide a device simple of construction and cheap to manufacture.

Referring to the drawings, Figure 1 is a cross section of a fragment of a hat showing my device applied thereto. Fig. 2 is a plan view of the same, and Fig. 3 is a perspective view of the comb-holding device.

Referring more particularly to the drawing, 1 indicates the crown of a hat; 2 indicates the part of the fastening means which is attached to the crown for holding my device in place; 3 indicates the frame which supports a mirror 4; and 5 designates the part of the fastening device which is attached to the frame 3 and is adapted to operate with the part 2. Secured at one end of the frame 3 is a comb-holding device which comprises a resilient member 6 and an arm 7 between which is inserted the comb 8.

Adjacent the comb-holding device is a means of identification consisting of a plate 9 of any suitable transparent material secured between the frame 3 and an edging strip 10 beneath which is adapted to be inserted a card 10'. The comb-holding device is secured to the frame 3 by any suitable means, such as the rivet 11.

When it is desired to remove the mirror from the hat, all that is necessary is to separate the parts 2 and 3 and the mirror is then 40 free to be used as an ordinary pocket mirror.

From the foregoing description taken in connection with the accompanying drawings, it will be seen that I have provided a very practical and useful attachment which 45 may be applied to hats of any nature and which will fulfil a long felt want. The frame may be formed of any suitable material, such as leather and celluloid, and may be of any desired size and shape.

It is to be understood that while I have shown and described the preferred embodiment of my invention, I do not wish to be limited to this exact construction, combination, and arrangement of parts, but may 55 make such changes as will fall within the spirit and scope of the invention as claimed.

Having thus fully described my invention, what I claim is:—

The herein-described hat mirror comprising a frame, a mirror secured within the frame, a pocket at one end of said frame provided with a transparent plate, said pocket adapted to receive an identification card, a clamp connected to the frame for 65 holding a comb and means for securing the frame within the crown of a hat.

In testimony whereof I affix my signature in presence of two witnesses.

JAMES R. BETT.

Witnesses:

J. E. PRICE,
